(57) **CLAIM**

The ornamental design for a medical camera device, as shown and described.

DESCRIPTION

FIG. 1 is a perspective view of a medical camera device showing our new design;

FIG. 2 is first side view of the medical camera device;

FIG. 3 is a second side view of the medical camera device;

FIG. 4 is a top view of the medical camera device;

FIG. 5 is a bottom view of the medical camera device;

FIG. 6 is an enlarged scale front view of the medical camera device; and,

FIG. 7 is an enlarged scale rear view of the medical camera device.

The broken lines depict portions of a medical camera device in which the design is embodied that form no part of the claimed design.
